UNITED STATES PATENT OFFICE

115,362

DESIGN FOR A RANGE

Walter F. Rogers, Oak Park, Ill., assignor to
Crown Stove Works, Cicero, Ill., a corporation
of Illinois

Application October 14, 1938, Serial No. 80,454

Term of patent 14 years

To all whom it may concern:

Be it known that I, Walter F. Rogers, a citizen of the United States, residing at Oak Park, in the county of Cook and State of Illinois, have invented a new, original, and ornamental Design for a Range, of which the following is a specification, reference being had to the accompanying drawing, forming part thereof,

The figure is a perspective view of a range embodying my new design. The opposite end of the range is similar to that shown in the drawing.

I claim:

The ornamental design for a range, substantially as shown and described.

WALTER F. ROGERS.
